UNITED STATES PATENT OFFICE.

OTIS A. MYGATT, OF NEW YORK, N. Y.

DESIGN FOR A PRISMATIC-GLASS REFLECTOR FOR ARTIFICIAL LIGHTS.

No. 87,981.

Specification for Design.

Patented May 1, 1906.

Application filed March 25, 1904. Serial No. 200,041. Term of patent 14 years.

To all whom it may concern:

Be it known that I, OTIS A. MYGATT, a citizen of the United States, residing at New York, in the county of New York and State of New York, have invented a new, original, and ornamental Design for Prismatic-Glass Reflectors for Artificial Lights, of which the following is a specification, reference being had to the accompanying drawing, forming a part thereof.

The figure is a side elevation of a reflector embodying my invention.

The reflector is of transparent glass. The body of the reflector is externally covered

with reflecting-prisms arranged in series and interspersed with pyramids, there being rows of pyramids at the lower ends of each series of prisms except the lower series and all being integral with the body.

I claim—

The ornamental design for a glass reflector of the form shown having external rows of reflecting-prisms interspersed with rows of pyramids, as shown and described.

OTIS A. MYGATT.
